UNITED STATES PATENT OFFICE.

HERMANN MOYÉ, OF LEIPSIC, GERMANY.

CAR-COUPLING.

SPECIFICATION forming part of Letters Patent No. 447,712, dated March 3, 1891.

Application filed September 3, 1890. Serial No. 363,853. (No model.)

To all whom it may concern:

Be it known that I, HERMANN MOYÉ, of Leipsic, in the Kingdom of Saxony and German Empire, have invented new and useful 5 Improvements in Railway-Wagon Couplings, of which the following is a specification, reference being had therein to the accompanying drawings.

This invention relates to a side coupling 10 for railway-wagons, whereby it is possible to connect and disconnect wagons without stepping on the line on which they are running, and whereby the otherwise dangerous work of the shunter, who has hitherto generally had to move between the rails and the 15 wagons, is avoided.

The characteristic feature of the invention is that by raising the lever-arms not only is a link laid over the coupling-hook of the wagon 20 to be coupled, but also a safety-hook is lifted in such manner that the safety-hook of the wagon to be coupled grips behind the first-mentioned safety-hook. By lowering the lever-arms the link is disconnected and the 25 safety-hook released. The lever-arms are secured in their upper position by means of a special fixing apparatus.

The invention is illustrated on the accompanying drawings, in which—

30 Figure 1 shows the end of a railway-wagon with disconnected couplings—*i. e.*, with lowered side levers. Fig. 2 is a front view of a coupled wagon—*i. e.*, with raised side levers; Fig. 3, the coupling arrangement in plan corresponding to Fig. 2; Fig. 4, the same in elevation, corresponding to Fig. 1; Fig. 5, the connection of the link to the off side of the crown-wheel. Fig. 5^a is the rear side of the crown-wheel; Fig. 6, a view in perspective of 35 two coupled wagons, the buffers being omitted. Figs. 7 to 10 show the fixing arrangement for the side levers A and A'. Fig. 7 shows the end of a railway-wagon with the side levers, the coupling disconnected without the connecting-link, and the thereto-belonging cog-wheels. Fig. 8 shows the fixing arrangement with lowered side levers—that is, the wagons disconnected. Fig. 9 shows the fixing arrangement by coupled wagons. 40 Fig. 10 shows a plan of the traction-beam with the side levers and fixing apparatus.

At A and A' two levers are indicated, each

of which has a toothed segment b and b'. These toothed segments engage small spur-wheels c and c', Fig. 3, which are closely connected with spur-wheels d and d' and are arranged behind them on the same shaft. At the back end a of the lever A there is a slot e, in which the guiding-pin e' at the back end of the lever A' runs. The crown-wheels f and f' gear with the spur-wheels d and d', and are in such manner hinged at their off side to the link B that the said link rests on a stud g², eccentrically to the shaft o, and is compelled occasionally to lie and rest with its 55 back off-bent end against the shaft o. The arms h and h', which are forked at their ends, are jointed at g and g' to the levers A and A', and they are fixed at their other ends to the crank i, Fig. 4. The latter is movably connected with the forked bent arm K, which is fixed to the wagon. The crank i has a pin at i', which is guided in the slot m of the knee-shaped bent arm n. The arm n is in turn hinged to the double lever C, which 60 is hinged to the shaft o of the crown-wheels f and f' and ends in the safety-hook C', Fig. 4. The double lever has the shape of a fork from the point where the hook C' stops, and the said hook has on its upper side a groove 65 C'', so that the corresponding safety-hook of the wagon to be coupled is securely guided.

The coupling works in the following manner: When the wagon to be coupled is sufficiently near the one at rest, the shunter at 85 the proper moment lifts the lever-arm A. The toothed segment is thereby also raised and turns the spur-wheel c and at the same time the spur-wheel d on the same shaft. This causes also the crown-wheel f to turn, and the 90 link B, assisted by its own weight, then falls down and clasps the coupling-hook D of the following wagon, and so the wagons are connected. By the raising of the lever A, however, the crank i is simultaneously compelled 95 by the arms h, which here take the place of guides, to travel over the same road. The pin i' therefore pushes up the arm n, and this, as the hook C' must co-operate in the movement mentioned, engages the said hook 100 in the hook C' of the wagon to be coupled. Thus a double connection is established by the link B and the safety-hook C'. With the raising of the lever A the lever A' is com-

5 pelled by the guiding-pin e' to co-operate in the same movement. Only one workman is necessary to carry out the work of coupling, as this can be done not only from the left 10 but also from the right side of the wagon. When the wagons are to be disconnected, the man presses the lever A down again. A reverse turning of the spur-wheels c and d and of the crown-wheel then takes place. The 15 link B is in this way raised and releases the hook D . The knee-lever n , also set in action by the crank i and the arms h and h' , completes a movement downward and draws the hook-arm C , with the safety-hook C' , out 20 of connection with the corresponding hook-arm of the wagon to be disconnected. To secure the side levers in their upper position, the following arrangement is employed and illustrated in Figs. 7 to 10. On each side 25 of the end of the wagon below the traction-beam is fixed a strong iron plate p , on which slides easily a rod q , with knob q' , in slide-pieces p' . The rod q is connected with a short turning joint r at the point q^2 . The 30 joint r is fixed firmly on a cross-bar s . Between the two upper and lower slide-pieces p' are guided catches t , with narrow grooves t' . These catches move with their sloped ends across a slot A^2 of the plate p , intended for the side levers $A A'$, respectively, to move in. The grooves t' of the catches t are meant to guide pins q^4 of the rod q . If 35 the knob q' is pushed upward, Fig. 9, the pins q^4 of the rod q move the catches t back, thereby leaving the slot A^2 free for the levers $A A'$, respectively, to play in. By coupling two wagons, Fig. 8, the side levers $A A'$, re-

spectively, are moved upward and are held in this position by the catches t , which slide across the slots A^2 underneath the side levers, acted upon by the rod q , which drops through the weight of its knob q' , thereby causing the pins q^4 to move downward in the narrow grooves t' , which are placed in a slanting position, and therefore move the catches t horizontally across the slot A^2 , and thus prevent the lowering of the side levers $A A'$, respectively. If the fixing arrangement is 40 acted upon only on one side of the wagon, this action is transmitted to the other side by 45 the turning joint r and cross-bar s .

What I claim, and desire to secure by Letters Patent of the United States, is—

1. In a coupling for railway-wagons, the combination of one or more levers $A A'$, the 55 toothed segments $b b'$, spur-wheels $c c' d d'$, and crown-wheels $f f'$, arranged to operate the link B , and the arms $h h'$, crank i , and knee-lever n to operate the safety-hook C , substantially as described. 60

2. In a coupling for railway-wagons, the combination of sliding catches t , provided with grooves t' and slide-pieces p' , acted upon by the weight of a rod q , provided with a knob q' and pins q^4 to prevent the side levers from 65 descending and thereby disconnecting the railway-wagons, substantially as described.

In witness whereof I have hereunto set my hand in presence of two witnesses.

HERMANN MOYÉ.
